INVENTOR.
Ross Koile,
BY *G. Kennedy*,
ATTORNEY.

UNITED STATES PATENT OFFICE.

ROSS KOILE, OF BRANDON, IOWA.

TRACTION-WHEEL DRIVING MEANS.

1,292,954.

Specification of Letters Patent. Patented Jan. 28, 1919.

Application filed April 19, 1918. Serial No. 229,525.

To all whom it may concern:

Be it known that I, Ross KOILE, a citizen of the United States of America, and a resident of Brandon, Buchanan county, Iowa, have invented certain new and useful Improvements in Traction-Wheel Driving Means, of which the following is a specification.

My invention relates to improvements in traction-wheel driving means, and the object of my improvement is to supply for any motor-vehicle using traction-wheels, means for positively driving same, which shall be powerful, effective, keep out dust, and distribute evenly the tractive effort on the moving parts.

This object I have accomplished by the mechanism which is hereinafter described and claimed, and which is illustrated in the accompanying drawings, in which Figure 1 is an axial vertical transverse section of a traction-wheel equipped with my improved driving means; Fig. 2 is a front elevation of the outer set of coacting gearing, and Fig. 3 is a section of the device, showing the inner set of coacting gearing, and taken on the broken line 3—3 of said Fig. 1.

Similar numerals of reference denote corresponding parts throughout the several views.

The numeral 1 denotes a rotatable axle, which may be one of an alined pair connected by differential-gearing (not shown), and rotatably mounted in a fixed frame-housing 2.

The housing 2 has an integral disk-shaped web 3 provided with an outwardly-directed concentric flange with internal-gear teeth 4.

The numeral 11 denotes a casting to receive shafts, which is removably and rotatably mounted on said housing 2. The outer part 30 of the casting is used as a triform gear-case to receive the three equidistantly spaced gears 22, 23 and 24, of the same size and number of teeth, mounted on driven shafts 5, 6 and 7 respectively, the latter seated rotatably in transverse orifices in said casting and having their rear ends extending therebeyond and having like gears 8, 9 and 10 fixed on their rear ends. The rear part 14 of the casting is of disk form, and closely surrounded by the rim of the disk 3, to keep out dust. The gear-casing part 30 is covered by a removable face-plate 25, secured by machine-screws 26. The gear-wheels 22, 23 and 24 all mesh with the teeth

of a central pinion 21 fixed on the outer end of the axle 1 in said casing 30. The other gear-wheels 8, 9 and 10 all mesh with the internal-gear teeth 4 on said fixed disk 3. 60 Within the casting 11 are the bearing-openings 17 and 19 to receive anti-friction rollers 18 and 20 respectively for the axle 1, while in said casting are also bearing-openings 12 and 15 to receive anti-friction rollers 13 65 and 16 respectively for the driven shafts 5, 6 and 7.

On the casting 11 are fixed radial grooved arms 27, in whose longitudinal grooves are fixed the inner ends of the flat spokes 28, 70 whose outer ends are riveted to the inner face of the traction-wheel rim 29.

Since the casting 11 is rotatable on said housing 2, when the axle 1 is positively rotated, its pinion 21 rotates the gear-wheels 75 22, 23 and 24, with the driven shafts 5, 6 and 7, also the rear set of gear-wheels 8, 9 and 10, the internal-gear 4 serving as a fixed abutment whereby the gear-wheels 8, 9 and 10 serve to rotate the casting 11 and with 80 it said traction-wheel 29, and said mechanism is reversible, which fits it for use in any motor-vehicle such as a tractor or the like.

The two sets of triplicate gears serve to 85 distribute the tractive effort on the bearings, axle and shafts, which prevents any unbalanced condition in said parts, and obviates excessive wear in the parts, and prolongs the life of said structures under the 90 many and varying strains of use, such as are incident to a tractor working over rough or uneven surfaces. The parts of the device are simple, easily assembled or disassembled, and inexpensive to make and use. The use 95 of the face-plate 25, and the disk-flange or rim 3 closely surrounding the rear circular part 14 of the casting 11, prevents entry of dust to the different bearings, which is especially suitable for a tractor moving 100 over dusty soil.

Having described my invention, what I claim as new, and desire to secure by Letters Patent, is:

1. The combination with a traction-wheel, 105 of driving means therefor, comprising a rotatable axle, a fixed housing for said axle including an internal-gear fixed thereon, a housing rotatably mounted on said housing having therein three equidistantly spaced bearing-orifices therein equidistant from said axle, driven-shafts rotatably mounted in

- said bearing-orifices, said boxing including a tri-formed gear casing like gear-wheels fixed on ends of said driven-shafts and in mesh with said internal-gear, a pinion fixed 5 on said axle, like gear-wheels fixed on the opposite ends of said driven-shafts and in mesh with said pinion within said gear casing, said traction-wheel being fixedly concentrically mounted on said boxing.
- 10 2. The combination with a traction-wheel, of driving means therefor, comprising a rotatable axle, a fixed housing for said axle including a fixed concentric disk having an outwardly-directed rim provided with internal-gear teeth spaced from its outer edge, a boxing rotatably mounted on said housing and provided with a plurality of equidistantly spaced bearing-orifices containing anti-friction rollers, driven-shafts rotatably 15 mounted on said anti-friction rollers to project oppositely therefrom, like gear-wheels fixed on ends of said driven-shafts and in mesh with said internal-gear teeth, a pinion fixed on the outer end of said axle, like gear-wheels fixed on the opposite ends of said 20 driven-shafts and in mesh with said pinion, the outer end of said boxing being formed into a gear-case for said pinion and its said intermeshed gear-wheels, a face-plate removably secured over said gear-case, the opposite end of said boxing being formed into a disk concentric with the axle and closely fitted within the projecting part of the rim 25 outside of said internal-gear teeth to provide a gear-case for the gears meshing with the
- said teeth, and said traction-wheel being fixedly mounted concentrically upon said boxing.
3. The combination with a traction-wheel, of driving means therefor, comprising a rotatable axle, a fixed housing for said axle including an integral concentric disk thereon having an annular lateral rim having internal-gear teeth and a part projecting beyond the gear teeth, a boxing rotatably 40 mounted on the spindle of said axle and having on one end an integral annular flange positioned within and in close movable fit with the said projecting part of said annular rim, said boxing having on its opposite end 45 an integral triformed flange provided with a laterally directed rim, a face-plate removably mounted on the last-mentioned rim to provide a gear-case between it and the boxing, said boxing having three concentrically spaced 50 longitudinal shaft bearings, a pinion fixed on the outer end of the axle-spindle within said gear-case, driven-shafts rotatably mounted in said shaft-bearings to project from opposite ends thereof, like gear-wheels fixed 55 on said shafts within said gear-case and meshed with said axle-pinion, and like gear-wheels fixed on the opposite ends of said shafts and in mesh with the said internal-gear teeth, said traction-wheel being fixedly 60 concentrically mounted on said boxing.
- Signed at Waterloo, Iowa, this 3rd day of April, 1918.
- ROSS KOILE.
